UNITED STATES PATENT OFFICE

2,554,341

ELECTRIC IRON

Joseph K. Moyer, North Canton, Ohio, assignor
to The Hoover Company, North Canton, Ohio,
a corporation of Ohio

Application May 8, 1947, Serial No. 746,815

3 Claims. (Cl. 219—25)

1

The present invention relates in general to electric irons and more particularly to a terminal connection for conducting electricity to the working parts of the iron.

Another object is to provide a novel terminal block for connecting the cord to the terminals of the heating element and to the thermostatic control.

Still another object of the invention is to provide a combination terminal block mounting and support for supporting a cover shell in spaced relationship to the sole plate of the iron.

Other objects and advantages of the invention will become apparent as the description proceeds when taken in connection with the accompanying drawings in which:

Figure 1 is a side elevation of an iron, partly in section, with this invention applied thereto;

Figure 2 is a rear elevational view through the rear part of the handle illustrating the chamber for mounting the conductor cord to the terminal block of the iron of Fig. 1;

Figure 3 is a plan view of the details of the wiring connections to the heating element and to the thermostatic control of the iron; and

Figure 4 is an enlarged isometric view of the terminal block insulation for the terminal connections of Fig. 1.

Referring to the drawings the invention is applied to an electric iron comprising generally a handle 11, a sole plate 12, and a cover shell 14. The handle 11 is preferably made of a phenolic condensation product and includes a front leg 20 and a rear leg 21 secured to the cover shell 14 in any suitable manner. The cover shell 14 is secured to the sole plate 12 in such manner that its downwardly extending edge is spaced slightly above the peripheral edge of the sole plate 12. The shell 14 is extended rearwardly beyond the rear edge of the sole plate 12 to form a supporting edge 23 which cooperates with a rear projection 22 on the handle 11 to support the iron on its heel when not in use. The space to the rear of the sole plate 12 formed by the overhanging portion of the cover shell 14 is closed by a closure plate 15 secured to the shell and to the sole plate in any suitable manner.

A suitable heating element is preferably embedded in the sole plate 12. One terminal of the heating element is shown extending above the surface of the sole plate at 16 of Fig. 1. A thermostatic control 17 of any suitable character operates to switch the current to the heating element on and off to maintain the sole plate at the proper temperature. The temperature at

2

which the sole plate is maintained may be varied by control knob 18 suitably secured to the control shaft of the control 17 and positioned above the cover shell 14 between the front and rear legs 20 and 21 of the handle 11.

As shown in Figs. 1 and 2 the rear supporting post 21 of the handle 11 is hollow and the cover shell 14 has an opening 38 therein beneath the hollow space in the post 21 and leading to the space between the overhanging portion of the shell 14 and the closure plate 15.

One side wall of the post 21 is apertured at 27 (Fig. 2) to receive a conductor cord 25 and a cord protector 26 which may be secured in the opening 27 in any suitable manner. The conductor wires 31 and 32 of the cord 25 extend downwardly through the opening 38 and are suitably attached to the extending lugs of terminal strips 33 and 34. As shown in Fig. 3 the strip 33 is connected at 79 to one of the terminals 16 of the heating element and the strip 34 is connected to one of the terminals 82 of the control 17. The other terminal 82 of the control is connected to the other terminal 16 of the heating element by a conductor strip 80.

In order to anchor the strips 33 and 34 to the sole plate 12 and also to secure the rear end of the cover shell 14 thereto a bracket generally indicated by the reference numeral 67 is provided. The bracket 67 is T-shaped in plan view, the ends 68 of the cross of the T being secured to an upwardly extending portion 69 on the rear of the sole plate 12 by means of screws 70 while the tail of the T extends forwardly to form a support for the rear end of the shell 14 to which it is attached by means of the screw 64.

The tail of the bracket 67 is positioned on a plane above the ends 68 by vertically extending portions connected by a horizontally extending portion 74 to form a downwardly opening recess for receiving superposed insulators 75 and 76 resiliently held together by a spring 78 positioned in the recess between the upper insulator 75 and the horizontally extending portion 74 of the bracket 67.

The lower insulator 76 has a pair of parallel slots 77 extending transversely thereof across its upper side. The central slot 77 receives conductor strip 34 while the end slot 77 receives the conductor strip 33. As shown in Figs. 2 and 3 the horizontally extending portion of the bracket 67 is provided with a downwardly struck portion 72 and the vertically extending portions at each end thereof have inturned portions 73 to prevent the insulators from getting out of place.

From the foregoing it can be seen that this invention provides a combined means for rigidly securing the terminal lugs of an iron to the sole plate and for supporting the cover shell in spaced relationship to the sole plate in which the parts can be readily removed for replacement or repair.

While I have shown but a single embodiment of my invention it is to be understood that this embodiment is to be taken as illustrative only and not in a limiting sense. I do not wish to be limited to the specific structure shown and described but to include all equivalent variations thereof except as limited by the scope of the claims.

What is claimed is:

1. In an electric iron, a sole plate, a cover shell secured to said sole plate, a rib extending upwardly from the heel of said sole plate, a heating element for applying heat to said sole plate, a control for controlling the energization of said heating element, terminal means for connecting a conductor cord to said control and to said heating element and a combined terminal anchor and cover shell support secured to said rib, said support including a portion spaced upwardly from said sole plate and forwardly from said rib to which said cover shell is secured and a laterally extending portion forming a downwardly facing pocket above said rib by which said terminal means is clamped against said rib.

2. In an electric iron according to claim 1 in which said support is T-shaped in formation with the ends of the cross of the T being bent downwardly for attachment to said rib and to form said downwardly facing pocket for receiving said terminal means and the tail of the T ex-

tends forwardly to form said support for said cover shell.

3. In an electric iron, a sole plate, an electric heater for said sole plate having terminals at the rear of said sole plate, a control for controlling the energization of said heater, terminal means for conducting electricity to said heater through said control and having a pair of terminal lugs extending rearwardly of said sole plate, a pair of superposed insulator plates resting on said sole plate and having recesses between them for receiving said terminal lugs, a clamping plate secured to the rear of said sole plate having a downwardly facing recess for receiving said insulator plates to clamp them against said sole plate and with an upwardly extending portion for supporting a cover shell above said sole plate and a spring in said downwardly facing recess above said insulator plates for holding them rigid with said sole plate.

JOSEPH K. MOYER.
